UNITED STATES PATENT OFFICE.

EDWARD L. NELSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

TRANSMISSION SYSTEM.

Application filed August 3, 1923. Serial No. 655,395.

This invention relates to transmission systems and more particularly to systems for radio transmission for duplex ship-to-shore communication over considerable distances.

5 An object of the invention is to provide a system for duplex radio transmission employing highly selective and efficient receiving apparatus of such a type as to avoid the necessity for synchronizing high radio frequencies. In radio telephone transmission 10 wherein carrier frequencies of 500,000 cycles per second and upward are employed and wherein the unmodulated carrier component is suppressed at the transmitter in accordance with methods well known at the present 15 time, difficulties have been encountered in connection with keeping the carrier frequencies correctly synchronized or correctly spaced apart. It is a particular object of 20 this invention to avoid the necessity for synchronization of such high carrier frequencies. In order to accomplish this desired result, the present system is so arranged that only some relatively low frequency sources 25 such as from about 8,000 to 90,000 cycles per second need be synchronized.

A further object is to provide a system of transmission such that although high frequency balanced modulators are employed 30 no exact or perfect balance is required.

A still further object is to provide a system in which the full advantages of suppression of the unmodulated carrier component are obtained without the disadvantages 35 of synchronizing high radio frequencies or transmitting synchronizing energy from one station to another.

A further object is to prevent high or other frequency singing at a radio terminal 40 or radio repeating station in which the frequency of the outgoing energy is controlled by received incoming energy.

In one organization of parts for carrying into effect the principles of the invention, 45 the ship station consists of a transmitter of almost any simple kind and a receiver of the double detection type. The transmitter and the receiver are connected to the same aerial structure. A loop resonant circuit is connected 50 in the receiving branch in order to reduce to a small amount the energy of the transmitting wave length traversing this branch. The portion of the outgoing carrier frequency wave which is unsuppressed

by this tuned circuit combines with the incoming waves to step them down to an intermediate frequency as a result of the first detection. A carefully stabilized oscillator operating at the intermediate carrier frequency supplies an unmodulated component of sufficient energy. For reasons which will be stated hereinafter, the intermediate frequency will remain constant, hence the oscillator, which supplies current of this frequency may be left fixed after being once 65 adjusted. As will be observed from the foregoing description the ship station is of a simple type.

The shore station will now be described. An oscillator supplies waves of a base frequency of 10,000 cycles per second. These oscillations are modulated by the message waves to be transmitted, in a balanced modulation circuit which suppresses the unmodulated component. A band filter selects one 70 resultant side band which is transmitted to the input circuit of a second balanced modulator. The second balanced modulator is supplied with oscillations of a frequency 75 of 50,000 cycles which are produced from the source of 10,000 cycles frequency by means of a harmonic producer, a selective circuit to select the fifth harmonic, and an amplifier. The output of the second modulator consists of two side bands one having 80 85 40,000 cycles and the other having 60,000 cycles as the carrier frequency. One of these side bands for example the latter, is selected by a band filter and supplied to a third balanced modulator circuit to which is also supplied a wave having the exact frequency 90 of that transmitted from the ship station.

In order to secure this, the wave energy from the ship station is received in an auxiliary receiving relay and passed through a suitable series of selective circuits and amplifiers. If the carrier frequency transmitted from the ship station is 760,000 cycles, this is combined in the balanced modulator circuit with the modulated side band based 100 upon a carrier of 60,000 cycles to produce new side bands, one of which will be based upon a carrier of 700,000 cycles per second. This wave is amplified in the power amplifier circuit and radiated to the ship station. The carrier wave radiated from the ship station may have a certain allowable frequency variation of the order of some 105

hundreds of cycles or more. Inasmuch as the carrier frequency radiated from the shore station at any instant of time is exactly that radiated from the ship station, plus or minus some fixed amount, the intermediate or beat frequency resulting from the combination of these two carriers will be constant.

Since the unmodulated component of carrier frequency is entirely or largely suppressed, it is necessary to supply this component before the final stage of detection. Inasmuch as the intermediate frequency is constant and is low, relative to the principal carrier frequencies, the problem of synchronization is reduced to one of synchronizing within the required limit, a source of oscillations of the order of 8,000 to 90,000 cycles per second rather than carrier oscillations of the order of 500,000 to 1,000,000 or more cycles per second.

The novel features which are believed to be characteristic of the invention are set forth in their particularity in the appended claims. The invention itself, however, both as to its organization and method of operation together with further objects and advantages thereof will best be understood by reference to the following detailed description, taken in connection with the accompanying drawing in which Fig. 1 shows diagrammatically the circuit arrangement employed at a shore station; Fig. 1^a is a modification, illustrating the adaptation of the circuit of Fig. 1 for a radio repeater; Fig. 1^b is a modification illustrating a simplified form of the circuit of Fig. 1; and Fig. 2 is a circuit diagram of a form of circuit which may be employed at a ship station.

In Fig. 1, microphone 1 indicates a telephone line or other source of outgoing messages designated by the frequency s_1 . These waves are applied to the input circuit of a balanced modulator 2 of the type described on pages 308 and 314 of a paper by Colpitts and Blackwell, entitled Carrier current telegraphy and telephony in volume 40 of the Proceedings of the A. I. E. E. A source 3 consists of a vacuum tube generator or other device for producing waves of a base frequency of 10,000 cycles per second. Various means are known for causing such a relatively low frequency generator to be very constant in frequency and the employment of such arrangements as are necessary to maintain the frequency very constant is contemplated.

One of the two side bands produced by the balanced modulator 2 is selected by the band filter 4 and impressed upon a second balanced modulator 5. The balanced modulator 5 is supplied also with waves of the constant frequency of 50,000 cycles produced by impressing waves from the source 3 upon a harmonic producer 6, selecting the fifth har-

monic in a selective circuit or series of selective circuits 7, and amplifying the selected 50,000 cycle component in an amplifier 8.

The balanced modulator 5 produces in its output circuit two speech side bands, one based upon a frequency of 40,000 cycles and the other upon a frequency of 60,000 cycles. The 60,000 cycle side band is selected by a band filter 9 and supplied to a balanced modulator 10.

Each band filter in the present system is a structure for passing a band of frequencies and excluding other frequencies and may be constructed in accordance with the theory set forth in Patent No. 1,227,113 granted May 22, 1917 to G. A. Campbell. However, it is contemplated that under certain conditions other selective means may be employed in place of band filters, the only requirement being that some arrangement is used which will produce the desired degree of selectivity. Such arrangements as thus described by Alexanderson in Patent No. 1,173,079 February 22, 1916 may be employed.

The balanced modulator 10 is supplied with waves of the carrier frequency radiated from the cooperating ship station. These are produced by receiving the carrier wave from the ship in an auxiliary antenna 11, selecting the unmodulated component in a series of sharply tuned selective circuits 12, and amplifying the energy selected in an amplifier 13 of any suitable type. It is not necessary that the circuits 12 discriminate completely between the incoming carrier and accompanying side band or bands but some discrimination is desirable.

In the output circuit of the balanced modulator 10 will be produced two speech side bands, one based upon the carrier frequency of 820,000 cycles and the other upon the carrier frequency of 700,000 cycles per second. The lower of these, namely 700,000 cycles, is selected by the band filter 14, amplified by the power amplifier 15 and radiated from the transmitting antenna 16.

It is assumed that the ship station is sending on a carrier frequency of 760,000 cycles per second and is radiating some energy of this frequency during reception periods on the ship. Therefore, if the ship station be of the carrier suppression type which is not an essential feature of this system it must not suppress the carrier to such an extent that the shore station will not be able to pick up an appreciable amount of energy in the auxiliary receiving antenna 11.

In accordance with the present invention, it is contemplated that the carrier wave radiated from the ship need not be exactly fixed, it may vary by some indeterminate amount which we may designate as Δ , Δ representing a frequency variation of from 0 to some hundreds of cycles or possibly more,

and being either a positive or negative quantity. Therefore, on the drawing, symbol Δ represents the possible variation of the carrier frequency of the ship station which may have any value from zero up to some hundreds of cycles per second. Inasmuch as the carrier frequency radiated from the shore station is always the same as that of the ship station minus exactly 60,000 cycles, the intermediate or beat frequency produced at each station by the combination of these two will be fixed and invariable so long as the 10,000 cycle generator 3 at the shore station remains fixed and invariable.

In order to adapt the arrangement of Fig. 1 to operate as a repeater station, the apparatus to the left of the line X—X in Fig. 1 may be replaced by a generator of oscillations of the frequency of 60,000 cycles as illustrated by Fig. 1^a. In thus adapting the system to function as a repeater station the selective circuits 12 and the amplifier 13 should be modified to pass not only the carrier frequency incoming to the antenna 11 but also the signal carrying side band accompanying this carrier frequency. The waves radiated from the antenna 16 will differ from those received by the antenna 11 in having their frequency changed by the fixed amount of 60,000 cycles and their energy greatly amplified.

In Fig. 1^b is illustrated a simplified form of the circuit arrangement of Fig. 1. The balanced modulator 2, the band filter 4, the harmonic reproducer 6, selective circuits 11, and the amplifier 8 are eliminated.

Carrier waves of the frequency of 60,000 cycles are provided from the source 17 to a balanced modulator 5 along with the signal waves from the microphone circuit 1. The band filter 9 selects one side band and impresses it upon the balanced modulator 10. The operation of the remaining parts of the system is identical with that described in connection with Fig. 1. In this simplified form, the carrier frequency of 60,000 cycles must be maintained constant within the required limits.

Fig. 2 represents a circuit diagram of the ship station. The microphone 18 indicates a telephone line or a source of signaling waves to be transmitted and the source 19 typifies any suitable source of carrier waves which need not be maintained exactly constant in frequency. Modulating and amplifying apparatus for producing modulated high frequency waves of the necessary power are indicated by the numeral 20.

The modulating and amplifying apparatus 20 may be such as to radiate a single signaling side band accompanied either by the normal amount or by a relatively small amount of unmodulated carrier component. Suppression of the unmodulated carrier component is not essential and both side bands

may be radiated if desired. In order to fulfill the condition of the greatest possible simplicity of the ship circuit this arrangement is preferred. A simple transmitter such as described by Heising in the Proceedings of the Institute of Radio Engineers for August, 1921, page 342, may be employed.

A branch 21 is extended from the ship antenna for the purpose of receiving. In this branch is a tuned loop resonant circuit 22 which is designed to offer a very high impedance to the outgoing carrier and the accompanying side band or side bands. Tuning elements 23 serve to give the antenna one natural frequency of resonance at or near the frequency of the incoming waves which are thus impressed upon the detector D_1 after being selected in the selective circuit 24. The detector D_1 steps down the frequency of the incoming waves by combining them with the energy of the outgoing carrier waves so as to produce in the tuned circuit 25, a combination frequency.

In order to reproduce a signal of good quality, it is necessary to supply an unmodulated carrier component for further detection. This is done by means of the vacuum tube or other generator 26 which is carefully adjusted to the desired intermediate frequency carrier which, in the present instance, is 60,000 cycles per second.

In general, the source 26 may consist of a carefully shielded vacuum tube oscillation generator constructed in accordance with known principles whereby the frequency may be kept quite constant. The waves from the source 26 are supplied to the tuned circuit 25 and impressed upon the detector D_2 . Telephone receivers 27 are connected to the output circuit of the detector D_2 for receiving the signal.

The receiving apparatus at the shore station has not been illustrated in Fig. 1. Any suitable type of receiving system may be employed. A receiving system such as shown in Fig. 2 may be coupled directly to the antenna 11. The tuned circuit 24 is coupled loosely to a coil in the antenna 11. To the left of the line Y—Y will be placed the apparatus indicated as being to the left of the line Y—Y in Fig. 2. A loop or other antenna tuned to the incoming carrier frequency may be used as a signal receiving antenna in place of the antenna 11. This loop may be located at a small or great distance from the antennae 11 and 16 as may be convenient or desirable. Instead of the source 26, the sixth harmonic produced by the harmonic producer 6 may be selected by means of a suitable selecting circuit and applied to the input circuit of the detector D_2 of the shore terminal receiving circuit.

Among the advantageous operating features of the system herein described are:

1. Suppression of the carrier and one side

band at the shore terminal aids in securing highly efficient transmission from a given supply of power.

2. The apparatus on a ship is of simple design, thereby facilitating its use by relatively inexperienced operators and reducing the cost.

3. Highly accurate control of the carrier frequency on the ship station shown in Fig. 2 is unnecessary.

4. The problem of carrier synchronization is reduced to that of maintaining 10,000 or 60,000 cycle sources within the required limits.

15 5. The circuit of the shore station shown in Fig. 1 will not sing because current waves of the frequency sent out by the antenna 16 are greatly attenuated by the antenna 11, selective circuits 12, balanced modulator 10 and band filter 14. Any current of the frequency received in the antenna 11 does not produce sufficient energy of the outgoing carrier frequency in the antenna 16 to cause singing. Consequently, relatively large amplifications in the amplifiers 13 and 15 may be secured.

6. Relatively imperfect carrier suppression in the balanced modulators 2, 5 and 10 is permissible as the band filters 4, 9 and 14 aid in suppressing the carrier.

The novel features believed to be inherent in the invention are set forth in the appended claims.

What is claimed is:

35 1. The method of signal transmission between two stations by means of carrier waves of different frequencies which comprises allowing the frequencies of the carrier waves to vary but maintaining their difference constant.

40 2. The method of transmission between two stations by means of carrier waves which comprises allowing the frequencies of the carrier waves to vary but maintaining their difference constant, and supplying at one station a wave of the constant difference frequency.

45 3. The method of signal transmission between two stations by means of carrier waves which comprises allowing the frequencies of the carrier waves to vary but maintaining their difference constant, and supplying a wave of the constant difference frequency at both stations.

55 4. The method of signal transmission between two stations by means of carrier waves which comprises allowing the frequencies of the carrier waves to vary but maintaining their difference constant, combining the carrier waves at one station to produce a difference frequency, and supplying an unmodulated component of the

constant difference frequency at said station.

5. The method of signal transmission between two stations by means of carrier waves 65 which comprises allowing the frequencies of the carrier waves to vary but maintaining their difference constant, combining the carrier waves at each station to produce a difference frequency wave, and supplying an 70 unmodulated component of the constant difference frequency at each station.

6. An arrangement for signaling between a fixed station and a movable station by means of relatively simple apparatus at the 75 movable station in combination with apparatus at the fixed station which comprises a signal receiving circuit, a supplemental circuit for receiving carrier waves from a movable station, means for producing a 80 fixed and relatively constant frequency wave at the fixed station, and means for combining said wave with said received carrier waves to produce an outgoing carrier wave of frequency differing from the received 85 carrier wave by a fixed and determined amount irrespective of frequency variations in the frequency of the received wave.

7. In a radio transmission system for two-way communication between a station, 90 whereat simplicity of apparatus is the chief desideratum, and another station which comprises at the first named station a transmitting circuit of any desired kind including means for producing a carrier wave, and 95 a receiving circuit comprising a detecting device for producing a combination frequency wave, an oscillation generator for producing a wave to combine with the combination frequency wave, and a detector for detecting the combined wave; and at the other station a receiving circuit for receiving the wave transmitted from the first named station, means for producing a relatively low frequency carrier wave modulated 100 in accordance with a signal to be transmitted, means for combining the modulated wave with the received wave to produce a modulated difference frequency wave which differs from the received wave by a constant 110 amount, and means for radiating the modulated difference frequency wave.

8. The method of maintaining the difference between incoming and outgoing carrier waves constant in a carrier wave terminal station having an inherently varying outgoing carrier wave source, which comprises receiving the varying wave at a distant station, and sending back from said station a carrier wave differing therefrom 115 by a constant amount.

In witness whereof, I hereunto subscribe my name this 27 day of July A. D., 1923.

EDWARD L. NELSON.
